UNITED STATES PATENT OFFICE.

CARL F. JEANSSEN AND ELMER F. STONE, OF WASHINGTON, DISTRICT OF COLUMBIA.

AIRPLANE CATAPULT.

Application filed February 8, 1924. Serial No. 691,441.

To all whom it may concern:

Be it known that we, CARL F. JEANSSEN and ELMER F. STONE, citizens of the United States, residing at Washington, in the District of Columbia, have invented new and useful Improvements in Airplane Catapults, of which the following is a specification.

This invention relates to catapults for launching airplanes from the decks of barges, ships, limited land areas, or like restricted spaces, and the main object of the invention is to provide means whereby the expansive force of gases, produced by the ignition of an explosive, preferably gun powder, may be employed for communicating working motion to the airplane launching carriage in a safe, reliable and highly efficient manner.

Another object of the invention is to provide means whereby the expansive force of the generated gases may be governed and controlled so as to avoid irregularities of motion, shocks or jars, and so as to secure an easy and regulated motion of the launching carriage at the required rate of speed.

Still another object of the invention is to provide a catapult which is simple of construction, which embodies a minimum number of working parts, which requires the services of a minimum number of attendants, which may be constructed, operated and maintained in efficient working condition at a comparatively low cost, and by the use of which the operating power may be produced in required amount only as needed at the moment of use, thus enabling storage tanks and other complex accessories for the storage and generation of power, such, for example, as those used in compressed-air catapults, to be dispensed with.

Still another object of the invention is to provide simple, reliable and efficient means for holding and releasing the airplane at a proper time period, and for properly tensioning the draft cable and setting the working parts in accurate relative positions for the launching action, whereby smoothness and certainty of operation of the working parts will be obtained.

In the accompanying drawings, showing one form of embodiment of the invention,—

Figure 1 is a side elevation of the catapult.

Figure 2 is a detail section through one side of the carriage and one of the guide rails.

Figure 3 is a vertical longitudinal section through the explosion engine or power element of the catapult.

Figure 4 is a sectional plan view of the same.

Figure 5 is a transverse section on line 5—5 of Figure 3.

Figure 6 is a transverse section on line 6—6 of Figure 3.

Figure 7 is a sectional plan view of the carriage locking and releasing and the draft cable tensioning device.

Figure 8 is a side elevation of the same, partially in section.

Figure 9 is a central vertical longitudinal section through the carriage locking and releasing and the draft cable tensioning device.

Figure 10 is an end elevation thereof.

Figure 11 is a transverse section on line 11—11 of Figure 9.

Figure 12 is an indicator diagram showing the expansion chamber pressure in the travel of the piston.

Figures 13 and 14 are views similar to Figures 3 and 4 of a modified form of explosion engine or power element.

Figure 15 is a transverse section on line 15—15 of Figure 13.

Figure 16 is a transverse section on line 16—16 of Figure 13.

Figure 17 is a view similar to Figures 4 and 14 disclosing the use of an expansion control valve.

Figure 18 is a section taken substantially on line 18—18 of Figure 17.

Figure 19 is a horizontal section through a portion of the explosion engine showing the same and the expansion control valve on an enlarged scale.

Figure 20 is a section on line 20—20 of Figure 19.

Figure 21 is a view of the expansion control valve per se.

Referring now more particularly to the drawings, 1 designates a carriage on which the airplane 2 is placed for the launching action. This carriage is mounted to travel upon track rails 3 and is provided with slotted guide members 4 for engagement with flanges 5 of the rails, whereby the carriage is slidably mounted and held from vertical displacement. While a sliding type of carriage is shown, a wheeled carriage may be employed, if desired. In practice, the rails 3 may be secured to a deck or other rigid foundation or to a turntable carried

by such deck or foundation. Also in practice any suitable means may be used, if desired or required, for locking the airplane to the car and releasing it at the launching moment, none being shown, as any of the devices commonly employed for the purpose may be used.

Arranged in working relationship to the carriage is a power mechanism comprising 10 a cylinder 6 and a piston 7 working therein. The rod of this piston is coupled to a cross-head 8 movable on guide rails 9 extending between and carried by an exhaust chamber 10 and a stationary support 11, which support includes a bumper 12, of suitable type, and herein generally shown, for cushioning and arresting the outward motion of the piston 7 and cross-head 8. A draft cable 13 is fixed at one end to the carriage 1, 20 passes around guide pulleys 14 and 15, suitably mounted upon the ship or other main structure, and is fixed at its opposite end to a lug or other projection 16 on the cross-head 8. A portion of this cable between 25 the cross-head 8 and guide pulley 15 is looped and extended back and forth between and trained over gangs of motion multiplying pulleys or sheaves 17 and 18, respectively mounted upon the cross-head 30 and a fixed part 19 of the structure, whereby motion transmitting mechanism is provided between the piston and carriage for driving the carriage at increased speed. The cable and pulley arrangement may be 35 such in practice as to impart to the carriage an increased speed equal to twice the rate of speed of the piston, or any other degree of increase that may be required under different conditions of service.

40 The piston 7 is impelled on its working motion by the expansive force of gases generated from the ignition of an explosive charge, preferably gun powder. For the accomplishment of this object, an explosive 45 engine comprising an explosion chamber 20 and an expansion chamber 21 are provided, said expansion chamber being arranged between and communicating at its opposite ends with the outlet end of the explosion 50 chamber and inlet end of the cylinder 6, respectively. A breech mechanism and firing device 22, of suitable type, is provided for closing the mouth of the chamber 20 and firing the charge inserted therein. The 55 charge may be made up of a primer surrounded by an ignition charge of black powder and the main charge of smokeless powder, preferably a slow burning powder such as used for large caliber guns, or any 60 other slow burning explosive may be used. This charge may be placed in a cartridge case so as to make it an easily handled unit. The charge is exploded in the explosion 65 chamber and the gases expand to the proper pressure in the expansion chamber 21, from

which latter they enter the working cylinder and act upon the piston, the piston being peripherally grooved or otherwise provided with suitable means to prevent gas leakage. Under the force of the gases the piston 7 is moved forwardly in the cylinder 6, thereby transmitting launching motion to the carriage 1, when the latter is released for action, through the movements of the cross-head 8 and elements of the speed multiplying gearing, such motion being continued until the piston 7 uncovers the exhaust ports 23. A suitable number of these ports 23 are provided in the cylinder 6 and communicate with the exhaust chamber 10, and this chamber 10 is provided, as particularly shown in Figure 5, with a pair of spaced chimneys or outlets 24 for the discharge of the exhaust gases to the atmosphere. At the limit of movement of the piston the cross-head 8 comes in contact with the cushioning bumper 12, whereby the motion of the working parts is arrested without shocks or jars. A cushioned stop or bumper 25 of approved construction may be arranged at the far end of the trackway 3 for similarly arresting the motion of the carriage 1 at the limit of its launching travel.

The function of the expansion chamber 21, which is always in direct open communication with the explosion chamber 20, is to automatically govern and control the expansion of the generated gases, and to maintain and insure the transmission to the piston 7 of a smooth and even working pressure, under substantially even driving power, throughout its range of movement. This is important in order to prevent disastrous shocks or jars on the working parts of the apparatus, which would otherwise occur. The dimensions of this expansion chamber are so chosen, relative to the dimensions of the bores of the explosion chamber and cylinder, that the gas entering the expansion chamber from the explosion 105 chamber is confined and permitted to expand in the explosion chamber and attain a predetermined pressure below maximum pressure before acting on the piston in the working cylinder and to subsequently reach 110 a predetermined maximum working pressure, which maximum working pressure is substantially maintained to provide a substantially uniform working force on the motion transmitting mechanism during the 115 launching travel of the carriage, the pressure on the piston being maintained with comparatively small loss until the exhaust ports are uncovered. Figure 12 illustrates, for example, the controlling action as exemplified by an indicator diagram, which shows the comparatively even and regular pressure maintained, with such variation of pressure as unavoidably occurs in the expansion chamber due mainly to the cooling 120

of the gases on account of the slow time period of expansion of the gases in the expansion chamber as compared with the rate of expansion in an ordinary gun. In this diagram the line A—E represents the line of travel of the piston, the line A—C the gas pressure ascent line, the line C—D the gas pressure variation line in the travel of the piston, and the line D—E the fall pressure line at the time of exhaust. At A the charge is fired, at B the carriage is released, shortly after firing of the charge, at C the maximum pressure is reached, at D the exhaust ports are uncovered, and at E the piston stops. The pressure curve line C—D indicates that through the controlling action on the gases established by the expansion of the gases into an expansion chamber of proper dimensions, the gas pressure is smoothly and evenly maintained, with small losses, principally due to cooling, during the full stroke of the piston. As a result, the power resulting from the force of the explosion will be transmitted without shocks, jolts or jars, so that an even and regular travel of the launching carriage at a designated launching speed is obtained. The amount of the explosive charge employed is, of course, governed by the weight of the airplane and rate of launching speed which is to be transmitted and may be governed at will according to these factors, so that an airplane of any size and weight within the power range of the launching apparatus as built may be launched with ease and facility.

A locking and releasing mechanism is provided for locking the carriage 1 in starting position and automatically releasing it upon a determined pull on the draft cable 13, and such mechanism also serves as a means for initially placing a proper tension on the draft cable. This mechanism comprises a frame or carriage 26 provided with slotted guide members 27 to slidably engage the flanges 5 of the rails 3, such frame having a limited degree of back and forth sliding motion on such rails. Slidably mounted in this frame is a draw-bar or rod 28 provided at its forward end with a coupler head 29 carrying a pivoted latch 30 to engage a coacting coupler link 31 on the car 1. The latch 30 is adapted to be held in closed position by a spring-pressed, pivoted locking dog 32 having an arm 33 provided with a locking tooth 34 to engage the free end of the latch 30, and having a trip arm 35. The arm 35 engages and is movable in a guide slot in a relatively stationary trip member 36 having a V-shaped trip or abutment surface 37. This member 36 is carried by a stem 38 passing through an apertured lug 39 on the frame 26 and secured in position by nuts 40, whereby the member 36 is adjustably connected with the frame 26 to set

the trip surface 37 with relation to the trip arm 35 of dog 32 for as sensitive a releasing action thereof as may be desired.

On the bar or rod 28 is an abutment 41, adapted to be adjusted and held in adjusted position by a nut 41', and surrounding the bar or rod between such abutment and the rear face of the forward end or head 42 of the frame 26 is a coiled resistance and cushioning spring 43. Disposed also between the coupler head 29 and the front face of the head 42 is a cushioning spring 44, in the form of a series of pairs of concavo-convex spring disks, the concave surfaces of the disks of each pair being arranged to face each other. These springs 43 and 44 exert counter pressures to normally maintain the coupler head 29 in properly spaced relationship to the head 42. The spring 43 serves to set up a predetermined yielding resistance, governed by adjustment of abutment 41, to the forward, carriage-releasing movement of the coupler head 29, under the pull of the draft cable 13. The spring 43 further serves to return the head 29 to normal position after each forward movement thereof in a launching action, and as well as to cushion the forward motion of the head 29 under the pull of the draft cable up to the time of the carriage releasing action, while the spring 44 further serves to cushion and check the force of the rebound of the head 29 under the expansion of the spring 43; both springs mutually cooperating to prevent undue shocks or jars and possible damage to the parts of the locking and releasing device. A threaded tensioning rod 45, swiveled at its forward end to the rear end of the frame 26, extends through and engages with a stationary threaded stem or nut 46, and is provided with a hand wheel 47 whereby it may be rotated. By means of this stem the carriage 26 may be drawn rearwardly on the track rails 3 to set said carriage accurately in starting position and to place a proper tension upon the cable 13, in which operation the motor piston 7, through the action of the cable, is drawn backwardly and accurately set in starting position.

In the launching operation, the carriage is placed on the tracks 3 in its proper location and locked by engagement of the latch 30 with the keeper 31, the dog 32 being set to hold the latch 30, and the draft cable 13 is tensioned by adjustment of the stem 45. The airplane is then placed in position on the carriage and the airplane engine started to drive the airplane propeller. The cartridge is then placed in the gun and the breech mechanism closed and, when the airplane engine has reached full speed, the explosive charge is fired. The gases thereupon generated fill the explosion chamber up to the piston, but, as a slow burning ex-

plosive is used, it requires an appreciable time to reach the desired pressure. Before the full pressure has been reached, the pull upon the draft cable draws the coupler head 29 with its draw-bar 28 forwardly against the resistance of spring 43, which is thereby compressed, allowing the coupler head 29 to have forward motion, in which action the dog 32 is retracted by the trip device 36, 5 thus releasing the carriage 1 which moves forward on the launching action. The carriage with the airplane thereon thereupon begins to acquire speed, the speed being increased by the increase of gas pressure up 10 to maximum, and through the speed multiplying motion of the power transmitting mechanism, whereby, as the carriage reaches the limit of its travel, a speed motion is transmitted thereto which may exactly equal 15 or which may exceed to any desired extent the launching velocity, i. e., take-off speed, of the airplane. Shortly after the movement of the piston is arrested by its buffer, 20 the motion of the launching carriage is arrested by the buffer 25, whereupon the airplane is released from the launching car and becomes airborne.

In Figures 13 to 16, inclusive, we have shown a modified form of the invention in 30 which the expansion chamber 21' is arranged to partly enclose the piston cylinder 6', and in which the bumper 12' is mounted directly upon the head closing the outer end of the cylinder. In this modified construction, also, the cross-head 8' carrying 35 the one set of multiplying pulleys 17' is mounted for movement on the guides 9' which extend between the nested cylinder and expansion chamber and a support 19' 40 which carries the other set of multiplying pulleys 18'. The exhaust chamber 10' in this construction is also of slightly different form, having a single exhaust outlet or chimney 24'. This construction provides a 45 somewhat more compact type of apparatus which may be better suited for use under some conditions.

In Figures 17 to 21, inclusive, we have also shown a modified construction of apparatus which is generally similar to the organization illustrated in Figures 1 to 6, inclusive, but embodies auxiliary means for governing the flow of the expanded gases from the expansion chamber to the working cylinder. The means provided for this purpose comprises a small valve chamber 48 extending transversely between the outlet end of the expansion chamber and inlet end 55 of the power cylinder and provided with 60 aligned ports 49 communicating with said power chamber and cylinder. A piston valve 50 is mounted for movement in the chamber 48 to control the ports 49, and this valve is provided with a stem 51 extending 65 externally through a stuffing box 52 and

having mounted thereon a drum or pulley 53. The pulley 53 is journaled in a suitable support 54 through which the valve stem 51 extends and to which said stem is feathered so as to hold it from rotation while permitting it to have sliding motion. The stem and hub of the pulley 53 are provided with engaging threads 55 whereby, through reverse rotary motions of the pulley or drum 53, back and forth sliding motion may be 70 transmitted to the stem 51 and valve 50 for opening and closing the ports 49. A cable 56 is passed one or more times around a guide pulley 57 journaled on the support 11 and has its end portions fastened to the pulley or drum 53 so as to wind and unwind in reverse directions thereon on reverse movements of said drum. One stretch of this cable 56 is secured to an arm 58 projecting from the cross-head 8, so that, in the 75 forward and backward travel of said cross-head, motion will be transmitted through the cable to the pulley or drum 53 to transmit opening and closing movements to the piston valve 50. By this means, when the 80 cross-head moves outwardly on the working motion of the piston 7, the valve 50, which is always more or less open, i. e., never completely closed, will be gradually and 85 progressively opened to a fuller degree, so that when the pressure rises in the expansion chamber the pressure will be simultaneously increased in the working cylinder, while on the return motion of the cross-head and piston said valve will be gradually and 90 progressively closed. As a result the flow 95 of the gas pressure from the expansion chamber to the power cylinder will be automatically controlled to mathematically regulate the supply of the motive fluid for action on the piston so as to still further reduce any tendency to pulsations or irregularities in the power flow, making it possible to govern the expansion of the gases and secure a desired smoothness of action 100 of the working parts to such a degree as to entirely eliminate or render negligible any 105 irregularities of flow tending to cause irregularities of motion of the launching mechanism.

The valve 50 is normally balanced with relation to the high pressure in chamber 21, but normally slightly unbalanced with relation to the relatively low pressure in cylinder 6, and, for the purpose of maintaining 115 this unbalanced status, which assists in the operation of the valve, ports 59 are provided for connecting the ends of the valve chamber 38 with the adjacent end of the cylinder 6, which ports permit a portion of the 120 gas pressure contained in cylinder 6 to pass into chamber 48 and to act on both ends of the piston valve 50, whereby the motion of said valve is assisted during the travel of 125 the power piston, allowing a very sensitive 130

and easy motion of the valve to be obtained.

- By the construction of launching mechanism above-described, we provide a launching mechanism capable of using gun powder or other explosive in a highly efficient manner and without objectionable shocks, jars or other irregularities of motion which would make the use of such a power agent impracticable without proper and efficient means for controlling the explosion of the gases and their action on the power mechanism such as our invention provides. By the use of powder as the power agent, the amount of power to be developed for any launching action may be supplied and governed at will and produced at the time of use, obviating the necessity of employing storage tanks and other complicated equipment such as is necessary with launching apparatus employing other power producing agents, such as compressed air. The present invention not only provides a simplified form of apparatus for launching airplanes of all weights and sizes, but also one which may be installed and maintained in service at low cost, which occupies a minimum amount of working space, and which may be easily handled and therefore requires the services of a comparatively small number of attendants.

In this specification and the following claims the term airplane is intended to cover any type of flying machine.

Having thus fully described the invention, what is claimed as new is:

1. In an airplane catapult, the combination of a track, a launching carriage adapted to travel on the track, an explosion device for producing expansive gases from a slow burning explosive, motion transmitting mechanism for utilizing and transmitting the force of the gases for propelling the carriage, and means operating automatically for permitting the gas to expand and attain a predetermined pressure below maximum pressure before action on said motion transmitting mechanism and to reach a subsequent maximum pressure and for thereafter maintaining a substantially uniform pressure and working force on the motion transmitting mechanism during the launching travel of the carriage.
2. In an airplane catapult, the combination of a track, a launching carriage adapted to travel on the track, an explosion device for producing expansive gases from an explosive, means for controlling the expansion of the gases, and motion transmitting mechanism for utilizing and transmitting the force of the controlled gases for propelling the carriage.
3. In an airplane catapult, the combination of a track, a launching carriage adapted to travel on the track, an explosion device for producing expansive gases from an explosive, motion transmitting mechanism operated by the expansive forces of the gases for propelling the carriage, and means between said explosive device and motion transmitting mechanism for securing controlled expansion of said gases.
4. In an airplane catapult, the combination of a track, a launching carriage adapted to travel on the track, means for producing expansive gases from a slow burning explosive, means for governing the expansion of the gases, and means for transmitting the force of the expanding gases for propelling the carriage.
5. In an airplane catapult, the combination of a track, a launching carriage adapted to travel on the track, motion transmitting means, including a cylinder and piston, for propelling the carriage, and means for producing expansive gases from an explosive and conducting the same to the cylinder for action on the piston.
6. In an airplane catapult, the combination of a member for transmitting launching motion to the airplane, a chamber adapted for the firing therein of a slow burning explosive, a member adapted to be impelled by the force of the gases generated from the explosive, means disposed between said chamber and member for confining and permitting a predetermined expansion of the generated gases before action on the second-named member, and means for transmitting motion from the second-named member to the first-named member.
7. In an airplane catapult, the combination of a track, a launching carriage adapted to travel on the track, a draft cable connected with the carriage, motion transmitting mechanism, including a cylinder and piston, for transmitting motion to the draft cable, an explosion chamber for the firing therein of an explosive charge, and means between said chamber and the cylinder for controlling the expansion of the gases from the charge.
8. In an airplane catapult, the combination of a track, a launching carriage adapted to travel on the track, a draft cable connected with the carriage, motion transmitting mechanism, including a cylinder and piston, for transmitting motion to the cable, an explosion chamber for the firing of an explosive charge therein, and an expansion chamber disposed between said explosion chamber and the cylinder for permitting a determined expansion of the gases resulting from the firing of the charge.
9. In an airplane catapult, the combination of a track, a launching carriage adapted to travel upon the track, a draft cable connected with the carriage, sets of speed multiplying pulleys around which the cable is passed, means including a cylinder and piston for transmitting motion to the cable, an

- explosion chamber adapted for the firing of an explosive charge therein, and conducting means between said chamber and the cylinder operative for securing a controlled expansion of the gases from the exploded charge.
10. In an airplane catapult, the combination of a track, a launching carriage adapted to travel on the track, two relatively fixed and movable sets of speed multiplying pulleys, a movable cross-head carrying the movable set of pulleys, a draft cable passing around the pulleys and terminally connected with the carriage and cross-head, means for transmitting motion to the cross-head including a cylinder and piston, an explosion chamber for producing an expansive gas charge for admission to said cylinder, and an expansion chamber for regulating the expansion and pressure of the gas charge, disposed between the explosion chamber and the cylinder.
11. In an airplane catapult, the combination of a track, a launching carriage adapted to travel on the track, a draft cable connected with the carriage, a movable power member for transmitting motion to the cable, means for producing expansive gases from an explosive charge for action on said power member, and means for governing the expansion of the gases prior to the action thereof on said power member.
12. In an airplane catapult, the combination of a track, a launching carriage adapted to travel on the track, a draft cable connected with the carriage, a power element for transmitting motion to the cable, means for producing expansive gases from an explosive charge for action on said power element, and means for controlling the expansion of the gases.
13. In an airplane catapult, the combination of a launching carriage, power mechanism, including a power element, for transmitting motion to the carriage, an explosion chamber for producing expansive gases from an explosive charge for action on said power element, and means disposed between said explosion chamber and power element for governing the expansion of the gases.
14. In an airplane catapult, the combination of a track, a launching carriage adapted to travel on the track, draft mechanism for propelling the carriage, an explosive engine for actuating the draft mechanism, and means for governing the expansion of the gases generated by said engine so as to secure an even and regulated application of the force thereof to said draft mechanism.
15. In an airplane catapult, the combination, with a launching carriage, and means for propelling the same, of locking and releasing mechanism for the carriage comprising a shiftable support, a movable draw-head carried by said support, latch mecha-

nism carried by the draw-head for engagement with the carriage, means for yieldingly resisting forward motion of the draw-head and returning the same to normal position, means for releasing the latch mechanism upon a predetermined forward motion of the draw-head, and means for shifting the support and fixing the same in shifted position.

16. In an airplane catapult, the combination, with a launching carriage, and means for propelling the same, of a locking and releasing mechanism for the carriage comprising a frame member, a movable draw-head carried by the frame member, a latch device carried by the draw-head for engagement with the carriage, an independently pivoted dog for holding said latch in latching position, means for yieldingly resisting forward motion of the draw-head and for returning the same, after forward motion and release of the latch device, to normal position, and a trip device for releasing the latch dog upon a predetermined forward movement of the draw-head.

17. In an airplane catapult, the combination, with a launching carriage and means for propelling the same, of locking and releasing mechanism for the carriage comprising a frame member, a sliding draw-bar carried by the frame member, a tripable latch mechanism carried by the draw-bar for engagement with the carriage, springs arranged to respectively yieldingly oppose forward and backward movements of the draw-bar, and a trip device for releasing the latch mechanism upon a predetermined forward movement of the draw-bar under the pull of the carriage.

18. In an airplane catapult, the combination of a track, a carriage arranged to travel upon the track, power mechanism for propelling the carriage including a draft cable connected therewith, a frame movable upon the track, a resiliently mounted draft bar carried by said frame, latch mechanism carried by the draft bar for engagement with the carriage, means for releasing said latch mechanism upon a predetermined forward movement of the carriage and draft bar under pull of the cable, and means for adjusting the movable frame to impose a desired tension on the cable.

19. In an airplane catapult, the combination of a track, a launching carriage mounted to travel on the track, a power mechanism for propelling the carriage including a cylinder and piston, a draft cable connecting said power mechanism with the carriage, a frame slidably engaging the track, a spring restrained sliding draw-bar mounted on the frame, latch mechanism carried by the draw-bar to engage the carriage, a trip device for releasing the latch mechanism upon a predetermined forward movement of the carriage and draw-bar under pull of the cable,

and means for adjusting the sliding frame on the track.

20. In an airplane catapult, a carriage locking and releasing mechanism comprising a support, a spring-controlled sliding draw-bar on the support, a pivoted latch hook carried by the draw-bar, an independently pivoted dog for holding said latch hook in engaging position, and an adjustable trip device normally fixed from movement relative to the draw-bar for retracting the dog upon a predetermined forward movement of the carriage and draw-bar.

21. In an airplane catapult, the combination of a track, a launching carriage adapted to travel on the track, a draft cable connected with the carriage, motor mechanism for actuating the draft cable, and a locking and releasing mechanism for the carriage comprising a frame, a movable draw-bar on the frame, counteracting springs for normally resisting forward and backward movements of the draw-bar, carriage locking means carried by the draw-bar, and a trip device

25 for releasing said locking means on a predetermined forward movement of the carriage and draw-bar.

22. In an airplane catapult, the combination of a track, a launching carriage adapted to travel thereon, a motor, a draft cable connecting the motor with the carriage, and means for locking and releasing the carriage, and means operating through said locking and releasing means for drawing back the carriage so as to tension the cable.

23. Mechanism for launching an airplane comprising means for holding and firing an explosive charge, means for collecting and utilizing the force of the expanding generated gases therefrom to propel the airplane on its launching motion, and means for automatically governing the expansion and applied pressure of the gases during the range of the launching motion so as to avoid

material power fluctuations during the expansion period and to secure a substantially smooth and regular transmission of the applied power.

24. Mechanism for launching an airplane comprising means for holding and firing a charge of a slow burning explosive, a receiver for collecting and confining the gases from such slow burning explosive, said receiver operating to control the expansion of the gases evolved from the slow burning explosive so as to provide for a regulated and substantially uniform application of the power thereof without material irregularities or fluctuations during the expansion period, and means operated by the controlled gases for transmitting the power thereof for a launching action to an airplane to be launched.

25. In an airplane launching apparatus, the combination of an airplane launching carriage, an explosion chamber for the ignition therein of a slow burning explosive, motion transmitting mechanism coupled to the carriage, an expansion chamber between the explosion chamber and motion transmitting mechanism adapted to receive the gases resulting from the burning of the explosive and permit of the accumulation of the gases therein until a predetermined maximum working pressure thereof is reached, a carriage anchoring device, and yielding, releasable coupling means between the anchoring device and carriage operative upon a predetermined preliminary pull from the forces of the gases upon the carriage, and before the full working pressure of the gases in the expansion chamber is reached, to release the carriage from said anchoring device.

In testimony whereof we affix our signatures.

CARL F. JEANSEN.
ELMER F. STONE.
